UNITED STATES PATENT OFFICE.

WILLIAM ZOERB, OF DEDHAM, MASSACHUSETTS.

DESIGN FOR AN EYEGLASS OR SPECTACLE CASE.

SPECIFICATION forming part of Design No. 27,622, dated September 7, 1897.

Application filed April 10, 1897. Serial No. 631,630. Term of patent 14 years.

To all whom it may concern:

Be it known that I, WILLIAM ZOERB, a citizen of the United States, residing at Dedham, county of Norfolk, and State of Massachusetts, 5 have invented and produced a new and original Design for Eyeglass or Spectacle Cases, of which the following is a specification, reference being had to the accompanying drawings, forming a part thereof.

Figure 1 shows in side elevation my new and original design for an eyeglass or spectacle case, it being closed. Fig. 2 shows a similar view of my design for an eyeglass or spectacle case, it being open; Fig. 3, a longitudinal section of the case, taken on the dotted line yy , Fig. 1; and Fig. 4, a cross-section of the case, taken on the dotted line xx , Fig. 1.

The leading feature of my design consists in the shape or contour of the case, comprising two leaf-like halves or lids which form the sides of the eyeglass or spectacle case, and particularly in an extension or lip on the front edge of each lid.

Each lid a b of the eyeglass or spectacle case is substantially elliptical in shape and 25 has an extension or lip a' b' along its edge, the extension or lip a' being along the front edge of the lid a and extending from one end toward the center, and the extension or lip b' being along the front edge of the lid b and 30 extending from the opposite end toward the center, so that when said lids a b are closed together a continuous lip a' b' is presented to the eye, which extends substantially from end to end of the case, along the front edge 35 thereof.

I claim—

The design for an eyeglass or spectacle case, substantially as described and shown.

In testimony whereof I have signed my 40 name to this specification in the presence of two subscribing witnesses.

WILLIAM ZOERB.
